UNITED STATES PATENT OFFICE.

GEORGE H. ELLIS, OF ST. PAUL, MINNESOTA.

HEAT-INSULATING UNIT.

1,236,694.

Specification of Letters Patent. Patented Aug. 14, 1917.

Application filed September 24, 1915. Serial No. 52,433.

To all whom it may concern:

Be it known that I, GEORGE H. ELLIS, a citizen of the United States, residing at St. Paul, in the county of Ramsey and State of Minnesota, have invented certain new and useful Improvements in Heat-Insulating Units; and I do hereby declare the following to be a full, clear, and exact description of the invention, such as will enable others skilled in the art to which it appertains to make and use the same.

My present invention has for its object to provide an improved heat insulating unit adapted for very general use, but particularly adapted for use in connection with cars, and the like, and to such ends, generally stated, the invention consists of the novel devices and combinations of devices hereinafter described and defined in the 20 claims.

Particularly, the present invention is designed as an improvement on the heat insulating unit disclosed and claimed in my Patent 1,137,197, of date, April 27, 1915, entitled "Refrigerator car floor," and in my co-pending application S. N. 16,061, filed March 22, 1915, and entitled "Heat insulating unit."

The present invention is more especially directed to the improvement of the form of flexible water proof envelop which surrounds a heat insulating filler.

In the accompanying drawings which illustrate the invention, like characters indicate like parts throughout the several views.

Referring to the drawings:

Figure 1 is a fragmentary sectional view in perspective illustrating the improved heat insulating unit applied to a car floor in the manner disclosed and claimed in my prior patent above identified;

Fig. 2 is a perspective view of one of the heat insulating units;

Fig. 3 is a bottom plan view of one of the heat insulating units with some parts broken away; and

Fig. 4 is a fragmentary section on the line $x^4 x^4$ of Fig. 2.

Of the parts of the car, the numeral 1 indicates one of the side walls, the numeral 2 one of the side sills, the numeral 3 one of the intermediate sills, the numeral 4 the car floor proper, and the numeral 5 the boards 55 which constitute a sort of a subfloor and

are supported from the sills by cleats 6. The heat insulating units are closely placed together upon the subfloor 5 between the sills and, as shown, have their edges overlapped by strips 7 secured to the adjacent 60 sills.

This flexible water proof envelop is indicated by the numeral 8, and the fiber filler is indicated as an entirety by the numeral 9. As shown, the filler is made up of felted 65 fibrous heat insulating sheets and interposed strips. The flexible water proof sheet from which the envelop is formed is bent around the filler so that it completely incloses the same; and to form the envelop, its edges are 70 overlapped in the one direction, and the projecting ends of the envelop are then folded and overlapped at 8^a, much after the manner of folding paper around a cubical parcel. Attention is here called to Fig. 2, 75 by reference to which it will be noted that the bottom sheet of the envelop is turned upward and that the upper sheet or envelop is turned downward over the same, in such manner that there is no joint to leak close 80 to the bottom of the envelop even where cement is not employed on the overlapped end portions. However, all of the overlapped edge and end portions of the envelop are advisably securely cemented together by 85 the use of a suitable water proof cement, so that the envelop is thereby made water proof, even if completely submerged in water. However, the envelops will not, under any ordinary conditions be completely 90 submerged in water. In the application illustrated, the water which leaks through the boards and floor will run downward between the edges of the units and the adjacent sills, and from thence, between the joints 95 of the subfloor boards 5.

As a special feature of the present invention, the water is prevented from passing directly between the abutting ends of the insulating units, and air circulation between 100 such joints is also prevented, by means of flexible lap strips 10. These lap strips 10 are also preferably of water proof material. Here it may be stated that the envelop and lap strips are advisably made from a light 105 weight commercial asphalt roofing which is not only water proof, but is, in itself, a good heat insulating material. The said lap strips 10 are cemented to the envelop at one edge and they are preferably applied, one to 110

the top and the other to the bottom of the envelop, and in such manner that one projects from the top of one end and the other from the bottom of the other end of said envelop. When the envelopes are put together, as shown in Fig. 1, the end joints between the units will be lapped and projected, both at top and bottom, and thus the efficiency of the heat insulating filler or surface is increased.

What I claim is:

1. A heat insulating unit comprising an envelop and a heat insulating filler, the latter having secured thereto, a lap strip that projects from one face thereof and is adapted to overlap with an adjacent similar heat insulating unit.

2. A heat insulating unit comprising a flexible water proof envelop and a heat insulating filler, the said envelop having a flexible water proof lap strip attached to one face thereof and projecting beyond the end thereof and adapted to overlap the abutting

end of an adjacent similar heat insulating unit.

3. A heat insulating unit comprising an envelop of flexible water proof material and a heat insulating filler, the said envelop having flexible water proof lap strips attached to the opposing ends thereof and projecting the one from the upper and the other from the lower face thereof.

4. A heat insulating unit comprising a flexible water proof envelop and a heat insulating filler that is distinct from said envelop, the said envelop having the ends of its lower sheet turned upward and the ends of its upper sheet turned downward, and folded over the said upturned edges.

In testimony whereof I affix my signature in presence of two witnesses.

GEORGE H. ELLIS.
